UNITED STATES PATENT OFFICE.

ANDREW HUNTER, OF SAN FRANCISCO, AND CREST GUSTAFSON, OF OAKLAND, CALIFORNIA.

AUTOMATIC STATION-INDICATOR FOR RAILWAY-CARS.

SPECIFICATION forming part of Letters Patent No. 623,215, dated April 18, 1899.

Application filed March 29, 1897. Serial No. 629,821. (No model.)

To all whom it may concern:

Be it known that we, ANDREW HUNTER, residing in the city and county of San Francisco, and CREST GUSTAFSON, residing in Oakland, county of Alameda, State of California, citizens of the United States, have invented certain new and useful Improvements in Automatic Station-Indicators for Railway-Cars, of which the following is a specification.

10 Our invention relates to improvements made in mechanical apparatus for exhibiting in a railway-car at proper intervals during its travel on the road the names of the streets or stations as the same follow one another along the route and other matter for the information of the passengers, and also in mechanism for operating an apparatus of this character in an automatic manner by means of the electric current as a motive and operating 15 agent without requiring any attention on the part of the conductor or person in charge of the car.

The object of our invention is chiefly the production of an automatic indicating apparatus for use on electrically-propelled cars to be operated by the same force or power as that which is supplied to the motors of the cars and in connection therewith to obtain and secure several advantages over apparatus 20 of like character heretofore provided, and principally with regard to simplicity, certainty of operation, the quality of working in either direction, of being automatically reversed when the car has arrived at the end 25 of its trip and is about to return, of being entirely automatic in its operation, and yet under complete control of the conductor or the motorman as regards its adjustment.

To such ends and object our said invention 30 embraces certain novel parts and construction of parts producing an improved indicator and in certain novel construction and combination of indicator-actuating mechanism operated by electricity and means whereby 35 the same is automatically started and stopped at required intervals in the progress of the car along the road and is reversed at the end 40 of the route or at all times when the direction of travel of the car is reversed, all as herein- 45 after fully set forth and explained in the fol-

lowing description, in which the accompanying drawings are referred to by letter.

In the said drawings, which form a part of this specification, Figure 1 is a front elevation of our improved indicator; Fig. 2, a top view with the top of the case cut off on a horizontal plane to expose the parts within; Fig. 3, a transverse section taken vertically through the case and mechanism at xx , Fig. 1. Fig. 4 is an end elevation taken from the left-hand side of Fig. 2 with the end of the case removed, the figure being shown on an enlarged scale; Fig. 5, a similar elevation of the opposite end of the case; Fig. 6, a top view of Fig. 5 with the relay removed; Fig. 65 7, a detail in vertical cross-section through the apron-actuating drum or cylinder and a portion of the apron thereon on an enlarged scale; Fig. 8, a side elevation of the mechanical circuit-closing device by which the current is thrown upon and cut off from the indicator-actuating mechanism at desired intervals in the travel of the car along the road. Fig. 9 is a diagram of the operating and controlling circuits and switches. Fig. 10 is a section of the car, showing the wiring and circuit-closers; Fig. 11, a plan or top view of the switches and connections by which the current is taken from the motor-circuit of the car. 80

In the construction of the indicator two winding-rollers A A are mounted to turn on horizontal axles A' A' behind a sight-opening in the case X, that incloses all the mechanisms, and to these rollers are secured the ends of a band or web of cloth or paper B of proper length to contain on its face the names of all the streets or stations and such other matter as it may be desired to display, the band being wound upon one roller as it is taken up by the other roller. In the front part of the case between the two rollers before mentioned a larger roller or cylinder C is mounted in horizontal position and in such close relation to the opening X' that the cylinder projects beyond the front of the case, exposing about one-fourth of its circumference, and from the roller A, situated above the horizontal plane in which lies the axis of the cylinder, is carried the band B, over and 90 95 100

around the projecting front of the cylinder to the other roller A^x , that is situated below and somewhat behind the other roller. The function of this "roller" or "cylinder," as we have termed it herein, is to draw off the band B and cause it to travel smoothly and evenly in one direction or the other, according to the rotation given to the cylinder. It also operates to produce a given and regular rate of movement or travel of the band B across the sight-opening at such rotative movement of the cylinder, so that the divisions or sections of matter arranged for display on the face of the band shall be properly displayed through the opening. Such positive movement of the band is produced by a row of pins or studs D D, fixed in the surface of the cylinder in a single line or row around the circumference at the middle of the cylinder, and a row of holes b b in the band, also in a single line longitudinally through the middle of the band for its whole length. These holes are set at uniform distances apart, corresponding exactly to the linear distance between one pin or stud and the next measured upon the surface of the cylinder, and they are reinforced by grommets.

In the present construction about one-fourth of the circumference of the cylinder is exposed outside the case, and the four studs are placed at such points around its circumference that when the cylinder is left in a position of rest between the times of its rotations the studs are entirely concealed by the case, and that portion of the band displayed to view is the part lying between one hole and the next. In this arrangement also there are three studs always in engagement with the band, and the same is both kept smooth and even in its travel and is also drawn at regular tension from the roller at all times. This is effected by placing guide-rollers E E of relatively small diameter in suitably close relation to the cylinder to hold the band against the rear portion of its circumference and on a line with the studs that lie on that side of the cylinder. These guide-rollers are grooved to let in the studs and to hold down the band to the body of the cylinder. This manner of placing the studs and arranging the holes in the band in a single row enables us to secure an even as well as a positive movement of the band and is an important feature of the present invention.

The band B is kept in a state of tension and is wound on one roller as it is drawn off from the other roller by the reaction of a spiral spring F, coiled on a shaft K', to which the roller is connected by a spur-wheel K and a pinion L on the roller-axle. These two springs, one to each roller, are coiled in opposite directions in order that they shall be coiled or wound up by the unwinding of the band from the roller, and thus act to turn the roller and take up the apron again when the direction of travel of the same is reversed. The outer

end of each spring is secured to a fixed point m and its inner end to the axle K', that is geared into the roller by the spur-wheel and pinion before mentioned. In either direction of its travel, therefore, the cylinder C in drawing the band from one roller causes the spring of that roller to be wound up, while the other roller is turned in the contrary direction by the reaction of its spring and caused to take up the band and keep it in constant tension.

The power to rotate the cylinder C is furnished by a small series-wound electric motor G, connected with the cylinder by a pinion G' on the armature-shaft and a spur-wheel H on the shaft or axle of the cylinder. The wheel H is controlled in its revolutions by a stop-lever P acting against a ring or circular flange H' on the side of the wheel and controlled by a relay R. In the face of the flange are slots or depressions h^{xx}, into which the stop-lever drops in the rotation of the spur-wheel and stops the cylinder. These slots, arranged at uniform distances apart, correspond in number to the stops or intervals of rest that take place in one complete revolution of the cylinder, and the stop-lever is held in contact with the flange by a spring P². The relay R is arranged in a secondary circuit taken from the main or motor circuit of the car by a conductor T^x, in which is included a spring-jack or circuit-closer S, the voltage being properly reduced by a resistance R², placed between the main conductor and the relay. By closing the circuit at the springs S the relay R is energized and caused to attract the stop-lever, the result of which is to release the cylinder and allow it to turn. In addition to this function the stop-lever closes the main circuit upon the auxiliary motor G, and thus acts as a circuit-closer as often as it is lifted by the energized relay. For this purpose the lever is interposed in the motor-circuit by connecting the wire from one pole of the motor to the heel of the stop-lever at x' and the wires from the trolley-circuit to a contact-finger P', fixed in position just above the point of the stop-lever, as shown in Figs. 5 and 9. In this operation the circuit is closed upon the motor as long as the lever P is held up in contact with the contact-finger P', which is effected by the tooth on the under side of the lever P riding on the rim of the wheel H', and the circuit remains closed until the tooth of the lever drops into a notch h^{xx} in the rim in the movement of the wheel on its axis.

The length of the movement of the indicator-roller C is governed by the distance between the notches in the wheel H' and is sufficient to move the indicator-band or apron the distance required to bring to view at the sight-opening the name or matter displayed on the face of the apron.

The current for the motor G is taken from the trolley-circuit of the car through a reversing-switch, through the medium of which the motor G is operated to rotate the cylinder in

one direction or the other, thus placing the indicator-operating mechanism under complete control.

Ordinarily we provide both a hand-operated reversing-switch W, which is located in some convenient part of the car within the reach of the conductor, and also an automatic switch V, which is operated by the reversing movement of the trolley on its post or stand.

10 The first-mentioned switch enables the conductor to reverse the motor G and change the travel of the indicator-band at any time during the run of the car—as, for example, where the car may require to travel backward for a 15 short distance on the road—while the other switch V insures the required change of the indicator mechanism at the end of the trip independently of attention or special adjustment on the part of the conductor. These 20 connections of the motor G and the relay R through the switches and circuit-closers will clearly be understood from the diagram Fig. 10.

The wires x y from the positive and negative poles of the motor G are connected at the 25 switch W or V to the two arms w w^x, one insulated from the other. The wires w² w³ from the trolley-circuits are connected to the two studs or contacts t t', and the remaining 30 studs or contacts Z Z' are connected to a “ground” through the running-gear of the car. In one position of the arms the positive wire x of the motor G is connected at w to the trolley-circuit, while the negative side of 35 the motor is grounded through the wire y and the wire Z, or in the contrary position of the arms when the switch is reversed the positive side of the motor-circuit is grounded and the negative side is connected into the propelling-circuit of the car. The switch V on 40 the trolley-stand is connected to operate in the same manner, excepting that the arms w w^x, being secured to the trolley itself, are reversed in position as the trolley is changed at 45 the end of the road.

A switch U is placed in the relay-circuit for the purpose of throwing off the current at any time from the relay to stop the indicator and also for energizing the relay and 50 operating the indicator at the pleasure of the conductor without confining its operation entirely to the action of the automatic circuit-closer. This last-mentioned part of the mechanism is composed of the springs S S', the 55 circuit-closing plug S' on a pivoted lever S², carrying a wheel or roller S³, and a block or bumper S⁴, fixed on the track in the path of the wheel S³. These blocks are located at the required intervals of distance apart along the 60 road and at points where the indicator is required to be operated. The lever S² is suspended from the trucks or running-gear of the car, with the wheel S³ in close relation to the rail on the surface of the track to make 65 contact with the blocks S⁴ and lift the lever. A spring S⁵, bearing on the lever, holds it in working position and returns it to place as

soon as the wheel has passed over the block. The movement of the lever at every time of contact with a block thus closes the circuit 70 through the springs S S', and by momentarily energizing the relay R causes the stop-lever P to release the cylinder and close the circuit on the motor G.

It will be seen that the switches place the 75 indicator under complete control of the conductor. With the switch U the circuit can be closed and the indicator set in motion at any time independently of the action of the automatic circuit-closer that is worked by the 80 blocks on the track, and by the same means the power can be thrown off, so that the indicator will not be operated by the circuit-closer. This enables the conductor to set or adjust the indicator, and thereby bring any name or 85 other matter on the band into position at the sight-opening. In connection with this switch the reversing-switch W enables the indicator-band to be moved in either direction and the direction of its movement to be reversed by 90 hand, as circumstances may require, in adjusting the indicator.

When this apparatus is placed for operation on cars or trains other than those propelled by the electric current, the motive power 95 is supplied by an electric battery and the wires x y are connected with the poles of the battery instead of being connected with the propelling-circuit of the car. This is the only change required to adapt our indicator to 100 steam or other roads.

Having thus fully described our invention, what we claim as new therein, and desire to secure by Letters Patent, is—

1. In an indicator of the character described, the combination with the drum or roller C mounted for rotation within a case in an opening through which a portion of the roller is exposed, and a name-bearing band running on said roller; of the winding-rollers 110 A A^x, pinions L L, spur-gears K K, coil-springs F F on the shaft of the spur-gears, stop-wheel H' on the axle of the main roller C, stop-lever P, electrically-operated mechanism connected to said main roller to rotate 115 the same when the stop-wheel is released, and electrically-actuated mechanism connected with said stop-lever and operating to release the stop-wheel at regular intervals as described, and a spring to throw the said lever into engagement with the wheel, for operation 120 as set forth.

2. In a station-indicator, the combination of a case, a roller C for rotation therein having a portion of its circumference projecting 125 through said case, a name-bearing band having a single row of spaced holes through the center equidistant from the edges thereof, radially-set studs in single row around the middle of the circumference of roller C, 130 grooved rollers E E, winding-rollers A A^x, coil-springs F F on separate shafts geared into said winding-rollers, stop-wheel H' on the shaft of roller C having notches in its rim,

an electric motor geared into said stop-wheel, a motor-circuit normally open, a stop-lever included in said circuit and having a tooth to ride on the wheel and engage the notches 5 therein, an armature on said lever, a relay in a branch circuit which is normally open and includes a circuit-closing device, said relay acting to attract and raise the stop-lever clear of the notches in the stop-wheel and allow the 10 lever to ride the rim of the wheel, and a contact adapted to close the principal or motor circuit as often as the stop-lever is raised and rides on the stop-wheel, and to break the circuit when the lever drops into the notch of 15 the wheel, whereby said lever both opens the circuit of the motor and locks the stop-wheel.

3. In a station-indicator for electric cars, the combination of an indicator, an electric motor connected with or into the propelling- 20 circuit of the car, an automatic reversing-switch in said circuit located on the trolley and adapted by the change in the working position of the trolley at the end of the run of the car to reverse the current on the indicator-operating motor and thereby change the 25 direction of movement of the indicator.

4. In a station-indicator for electric cars, the combination of a band bearing the names of the stations, a band-operating roller, a 30 stop-wheel connected to said roller having notches in its rim, an electric motor geared

into said stop-wheel, a stop-lever in working position to ride on the rim of said wheel having a tooth to engage the notches in the rim thereof, an electric circuit normally open in 35 which is included said brake-lever as a part thereof, and a stationary contact-piece with which said lever is adapted to make contact when riding on the rim of the stop-wheel, an armature on said lever, a relay in a branch 40 or auxiliary circuit normally open, and a circuit-closing device in said circuit, constructed for operation as described.

5. The combination, with a rotatable trolley-stand, of the arms $w w'$ mounted thereon one insulated from the other, one of said arms being connected with the positive side and the other with the negative side of the motor-circuit, the stationary switch-plate beneath said arms having a set of contact-points 50 $t t'$ connected with the trolley-circuit, and a set of contacts $Z Z'$ connected to a "ground," substantially as described for operation as set forth.

In testimony that we claim the foregoing 55 we have hereunto set our hands and seals.
